[57] CLAIM

The ornamental design for a merchandise display rack, as shown and described.

DESCRIPTION

FIG. 1 is a top, front, and right side perspective view of a merchandise display rack showing my new design; FIG. 2 is a top, front, and right side perspective view of the wall portion of the rack, with the hanger portion omitted for clarity of illustration;

FIG. 3 is a top, front, and right side perspective view of the hanger portion of the rack, with the wall portion omitted for clarity of illustration;

FIG. 4 is an enlarged right side elevational view of the wall portion of the rack, with the hanger portion omitted for clarity of illustration;

FIG. 5 is an enlarged right side elevational view of the hanger portion of the rack, with the wall portion omitted for clarity of illustration; and,

FIG. 6 is an enlarged right side elevational view thereof, the left side being a mirror image of that shown.
